MICHAEL A. DROITCOUR, OF OAK PARK, ILLINOIS, ASSIGNOR TO MIEHLE PRINTING PRESS AND MANUFACTURING COMPANY, OF CHICAGO, ILLINOIS, A CORPORATION OF ILLINOIS.

PROCESS OF TONING PRINTING-PLATES.

1,005,619.

Specification of Letters Patent.

Patented Oct. 10, 1911.

Application filed December 15, 1910. Serial No. 597,521.

To all whom it may concern:

Be it known that I, MICHAEL A. DROITCOUR, of Oak Park, in the county of Cook and State of Illinois, have invented certain new and useful Improvements in Processes of Toning Printing-Plates; and I hereby declare that the following is a full, clear, and exact description thereof, reference being had to the accompanying drawings, which form part of this specification.

This invention relates to the production of toned or made-ready printing plates and resides in an improved method of producing such plates.

15. The object of this invention is to enable printing plates to be toned without liability of crushing any of the fine lines or dots in the printing surface thereof during the toning operation.

20. In the present invention instead of the metal of the printing plate being compelled to flow laterally, when under pressure, in order to enable the printing plate to be thinned at those points where high lights are desired, the metal is permitted to pass directly back into minute recesses or channels in a "pressure plate" in the shortest and most direct way, so that the face of the printing plate can be toned with very much 25 less pressure thereon than has heretofore been required in the toning process; the printing plate and toning devices are subjected to less pressure in order to effect the toning; and all liability of crushing or injuring delicate lines or dots in the printing surface of the printing plate during the toning thereof is practically obviated.

30. In this invention I employ (1) a toning member or reverse overlay to determine the 40 graduations or tones of the printing surface of the printing plate; (2) a pressure grader to relieve pressure on those portions of the face of the printing plate where such pressure would be liable to injure the same; and 45 to obtain increased pressure on other portions of the printing plate where it is necessary in order to produce the desired tones; and (3) a pressure plate which is provided with numerous points or projections and intermediate recesses or channels in its face 50 opposed to the back of the printing plate whereby the metal of the plate being toned is enabled to flow or recede into the channels of the pressure plate at the points where 55 displacement of metal is necessary in order

that the printing surface of the printing plate may be toned in accordance with the tones of the toning member applied thereto.

The invention will be explained in detail with reference to the accompanying drawings which illustrate, diagrammatically, one means for utilizing the invention.

In said drawings—Figure 1 is an edge view of a reverse overlay or toning member, Fig. 2 represents an edge view of an ordinary printing plate. Fig. 3 is an edge view of a pressure plate; and Fig. 4 is a face view thereof. Fig. 5 is a sectional view illustrating a printing plate, a toning member, a toning pressure grader, and a pressure plate in a press preparatory to the application of pressure thereto; and Fig. 6 is a similar view showing the parts under pressure. Fig. 7 is an edge view of the resultant toned printing plate removed from the press, with the toning member applied to its face; and Fig. 8 is an edge view of the finished toned printing plate.

The printing plate 1 to be toned may be an electrotype or stereotype plate of usual construction, but preferably made about seven-thousandths of an inch thicker than it is desired to have the plate when finally toned and ready for use. Such plate, prior to the toning thereof, has a plane printing surface, as indicated in Fig. 2. From this plate a reverse overlay or "toning member" 2 is made in any suitable manner; usually it is made of thin sheets of paper cut and pasted together so as to make this toning member thicker at the points where it is desired to have the plate thinner, and vice versa. In other words this reverse overlay or toning member is made thick opposite the parts of the printing plate which it is desired shall produce high lights in the impressions taken therefrom, and is made thinner opposite those portions of the printing plate which it is desired shall produce solids or darker shades in the impressions.

45. The toning member 2 is placed upon the face 1a of the printing plate 1 and in register therewith; and then the printing plate is placed face downward, with the toning member beneath it, upon the bed 5 of a suitable press, this bed being preferably heated. A pressure plate 3, Fig. 3, may then be placed upon the back of the plate; or may be attached, if desired, to the under surface of the platen 6 of the press. This pres-

sure plate 3 has in its lower face, or contact surface, numerous intersecting shallow channels, as indicated in Fig. 4, which channels may be about one-sixteenth of an inch 5 deep and extend parallel both longitudinally and transversely of the pressure member, and divide the under surface thereof into minute squares or dots 3^a each approximately one-thirty-second of an inch square, 10 and having their centers approximately one-sixteenth of an inch apart. Preferably the grooves in the pressure plate are slightly wider at their mouths than at bottom, thus imparting a slight taper or pyramidal shape 15 to the dots 3^a so that any metal which may enter the channels will withdraw freely therefrom.

Preferably I interpose between the back of the printing plate 1 and the pressure plate 3, a toning pressure grader 4 (Figs. 5 and 6). This pressure grader may be formed like the toning member of any suitable material; but I preferably make it of layers of paper graduated according to the 25 pressure necessary to effect the desired toning of the printing plate. This toning pressure grader supplements the action of the toning member 2, being made thicker where the printing plate requires more pressure 30 to give the desired tone; and thinner where the surface of the printing plate is of such a nature that pressure would have a tendency to crush or mash the same. In other words, the pressure grader 4 is a means 35 whereby the pressure imparted by the press can be varied in its effect upon the printing plate according to the subject matter in said plate. The pressure grader when properly 40 made will protect the weak points of the printing plate, where excessive pressure would injure same, and increase the pressure on the printing plate where such pressure is required.

Operation: The printing plate 1 to be 45 toned is placed face downward upon the bed 5 of the press, with the toning member 2 beneath it but against its printing surface; the pressure grader 4 is then laid upon the printing plate and against the 50 back thereof; the pressure plate 3 is arranged or placed above the pressure grader with its channeled face next the pressure grader, see Fig. 5. The said parts are then 55 forcibly clamped between the press bed 5 and platen 6; the bed being preferably heated to a temperature of about 350° F. Sufficient pressure is applied to cause the 60 face of the printing plate to conform to the toning member or reverse overlay applied to the face thereof, as the back of the printing plate is most forcibly pressed toward the toning member where the most pressure is required to tone the printing plate, because of the nature of such printing plate, 65 and to reproduce on the face of the printing

plate the tones of the toning member or reverse overlay, notwithstanding the pressure applied to the printing plate. Any injury to the printing surface thereof is prevented because the channels in the pressure plate 3 provide a ready outlet for surplus metal, and allow metal at the back of the plate opposite the projections on the toning member to protrude into said channels, as indicated in Fig. 6; and because the metal can thus crowd back into these channels or recesses there is no lateral flow of the metal in the printing plate such as has heretofore been necessary when a plane surfaced pressure member was employed; 80 hence the toning operation can be effected with very much less pressure upon the printing plate than has hitherto been required. As a result of this pressing operation the face of the printing plate is made 85 to reversely conform to the opposed surface of the toning member 2; in other words there will be slight depressions in the face of the printing plate at the places where the toning member is thick, and corresponding 90 projections on the back of the printing plate at the points where its face is depressed; so that the back of the toned printing plate (Figs. 6 and 7) substantially conforms in contour to the surface of the toning member 2, and is uneven. To remove the inequalities from the back of the toned printing plate the back of the printing plate is shaved; as indicated in Fig. 7, while its 95 face is still in contact with the toning member 2; thereby reducing the back of the printing plate to a plane surface, and making the printing plate of proper thickness for printing, while leaving the face of the printing plate toned in the desired manner. 100 Fig. 7 indicates a toned printing plate removed from the press and ready for the final shaving operation; and indicates at 105 1^b how the metal has been forced upward on the back of the printing plate into the channels of the pressure plate 3; and how the printing plate can be brought to the desired thickness by shaving it along the line c—c by a cutter C, or other suitable means. 110 Afterward the toning member 2 is removed and the finished printing plate, represented in Fig. 8, remains;—the surface of this plate being toned ready for printing. 115

I thus produce a printing plate having different tones in its printing-surface, as indicated in Fig. 8, and during the toning operation the surplus metal, where the pressure is greatest, instead of having to flow out in all directions from beneath the edges of the flat press platen can simply move into the adjacent channels in the pressure plate 3; thus obviously overcoming the lateral flow of the metal and locally holding the pressure necessary to tone the printing plate, whether such pressure must be greater 120 125 130

or less on different parts of the printing plate; so that where greater pressure is necessary to tone its face I locally hold it there, and it does not laterally flow to points where 5 it could damage the plate. While some printing plates might be effectively toned without the employment of the pressure grader 4, yet for fine work the most satisfactory results are obtained by using the 10 pressure grader 4, as the success of the toning operation is in the main, if not altogether, due to the toning pressure grader 4 in combination with the pressure plate 3 which allows for metal displacement without 15 lateral flow thereof. Obviously the use of the pressure plate 3 greatly lessens the amount of pressure heretofore required to tone a printing plate; lessens the danger of crushing the printing surface of the printing 20 plate during the pressing operation; and removes the danger of distorting fine lines in the printing surface of the printing plate by lateral flow of metal therein during the toning operation.

25 The pressure grader 4 as above stated enables greater pressure to be applied to any portion of the printing plate where it may be desired, without affecting the tone imparted to the printing surface of the printing 30 plate by the toning member. It would not do to thicken the toning member to gain increase of pressure at such points because the thickening of the toning member would alter its toning effect upon the printing 35 plate. But by using both a toning member and a pressure grader I can obtain the most delicate toning effects in the face of the printing plate and at the same time obtain any desired graduations in the pressure 40 upon the printing plate that will facilitate the toning operation, and enable the same to be performed expeditiously and economically in any ordinary press. And the employment of a channeled pressure 45 plate in connection with the toning member and pressure grader localizes excessive pressure on the printing plate by obviating lateral flow of the metal therein, which otherwise would tend to flow laterally and distribute 50 the pressure equally throughout the printing plate.

What I claim is:

1. The method of toning finished printing plates, consisting in applying a toning member to the printing surface of such printing plate, applying a channeled pressure plate against the back of such printing plate, and subjecting these parts to pressure whereby the face of the printing plate 55 is caused to reversely conform to the surface of the toning member by reason of the metal on the back of the plate being permitted to

flow or pass directly into the channels in the face of the pressure plate at those points where displacement of metal is necessitated 65 without lateral flow of the metal.

2. The herein described process of toning printing plates, consisting in applying a toning member to the face of a printing plate, applying a pressure grader to the back 70 thereof, and then subjecting the said parts to pressure sufficient to cause the printing surface of the printing plate to reversely conform to the toning member.

3. The herein described process of toning 75 printing plates, consisting in applying a toning member to the face of a printing plate, applying a pressure grader to the back thereof, applying a pressure plate having a channeled surface to the pressure grader, 80 and then subjecting said parts to sufficient pressure to cause the printing surface of the printing-plate to reversely conform to the opposed surface of the toning member.

4. The herein described process of toning 85 printing plates, consisting in forming a flat surfaced printing plate, applying a toning member to the face thereof, applying a pressure grader to the back thereof, applying a pressure plate having a channeled 90 surface against the pressure-grader, and then subjecting the said parts to pressure sufficient to cause the printing surface of the printing plate to reversely conform to the toning member; the metal at the back of 95 the plate passing into the channels in the pressure plate at the points where displacement of the metal is necessary to effect toning of the printing plate in accordance with the toning member.

5. The herein described process of toning 100 printing plates, consisting in forming a flat surfaced printing plate, applying a reverse overlay to the face thereof, applying a pressure grader to the back thereof, applying a 105 pressure plate having a channeled surface to the pressure grader; then subjecting the said parts to pressure to cause the printing surface of the printing plate to reversely conform to the opposed surface of the reverse overlay, and surplus metal in the back 110 of the plate to flow into the channels in the pressure plate at those points where displacement of the metal necessary to effect the toning of the printing plate; and 115 finally reducing the back of the printing plate to a plane surface.

In testimony that I claim the foregoing as my own, I affix my signature in presence of two witnesses.
